UNITED STATES PATENT OFFICE.

BENNETT D. MARKS, OF CHICAGO, ILLINOIS.

DESIGN-ROLLER.

No. 819,297.

Specification of Letters Patent.

Patented May 1, 1906.

Application filed June 14, 1905, Serial No. 265,286.

To all whom it may concern:

Be it known that I, BENNETT D. MARKS, a citizen of the United States, residing at Chicago, in the county of Cook and State of Illinois, have invented certain new and useful Improvements in Design-Rollers for Graining Wood or other Material upon Which it is Desired to Reproduce the Grain of the Wood, of which the following is a specification.

10 In design - rollers for graining - machines with which I am familiar it is customary to use a veneer, which is a thin section of wood bent in a curved or cylindrical form to encompass the cylinder or roller. Practice has 15 shown that rollers constructed in this manner wear out very quickly on account of the extreme thinness of the veneer and also get out of true very quickly, due to the swelling of the veneer, which is practically unavoidable, owing to the fact that it is immersed most of the day in paint. Besides this there is a tendency for the wood to warp or crack the veneer, which is necessarily a very delicate surface.

25 The object of my invention is to overcome these difficulties and to provide a roller which will be free from the objections of the rollers constructed with the thin veneer. My method of obtaining this object may be more 30 readily understood by having reference to the accompanying drawings, which are annexed hereto and are a part of this specification, in which—

Figure 1 is a side elevation of my roller. Fig. 2 is a cross-section taken on line X X in Fig. 1. Fig. 3 is a sectional view taken on the line H H in Fig. 2. Fig. 4 is a detail view of one of the sections of the design material before it is fitted to the roller. Fig. 5 is an enlarged detail showing the method of joining these sections. Fig. 6 is a detail view showing a method of securing the inner sections of wood to the hub. Fig. 7 shows a modified form of fastening for the design-boards.

45 Similar figures refer to similar parts throughout the entire description.

In the drawings, 1 is the roller. This roller is formed of a series of boards 2, which are tapered and fitted in radially around the hub 3, 50 in which is fastened the shaft 4 of the roller. This construction opposes a perfect resistance to the "go" or tendency of the wood to separate from the wood to which it is secured due to atmospheric changes of the different 55 pieces of wood, and owing to the taper the requisite strength of the wood is relatively in-

creased as the distance is increased from the center of the roller, so that as it reaches or nears the periphery thereof it is strongest. These boards are provided, as better shown 60 in Fig. 3, with two extensions 5 and 6. These extensions extend inwardly to the hub 3. These tapered sections may be secured to the hubs by means of lag-screws or any of the ordinary methods for such purposes. This 65 hub may be constructed, as shown in Fig. 3, with a flange 7, having a bevel-gear 8 on its outer face and a series of ribs 9 on its inner face. These ribs may be arranged to provide sockets for the ends of the extensions 5 70 and 6, so as to secure the hub as firmly thereto as if it were constructed integral therewith. By using this method of construction it becomes impossible for the roller to slip and consequently blur the impression. The surface of the boards 2 is turned true. The design-boards 10, being in the form shown in Fig. 4, are cut by means of a band-saw, as indicated by the dotted lines 11 in Fig. 4. These sections are then joined at an angle 12, 80 as shown in Fig. 5, the result being that the extreme thinness of the point 13 on the outer part of the joint is such that there is no perceptible joint, which would interfere with the transfer of a continuous grain. The boards 85 10 are then glued to the outer turned surface of the boards 2. It may be found desirable, however, in practice to hold these boards in position by means of the construction shown in Fig. 6, in which the board 10 is provided 90 with longitudinal slot or groove 14. A bolt 15, having a head 16, adapted to engage said slot, is fitted thereon. This bolt extends inwardly through the board 2 and is provided with a washer 17 and nut 18, so that it is possible to draw the boards firmly down and fasten them securely to the surface of the board 2 by tightening the nut 18, the result being that when this construction is followed a practically true roller is made, which will 95 100 maintain its true surface under any and all conditions. It may be found desirable in imitating parquetry flooring or wainscoting to have the grain of the sections run in various directions, which, it is obvious, may be 105 done without departing from the spirit of the invention.

Having described my invention, what I regard as new, and desire to secure by Letters Patent, is—

1. In a design-roller for graining-machines, the combination with two hubs, of wooden

sections mounted on said hubs, said sections extending radially from said hubs, said sections tapering inwardly, flanges on said hubs, means to secure said sections to said hubs, 5 sections of design-wood having the grain running around the roller adapted to form an outer covering for said tapering sections and means to secure said design-sections to said tapering sections, for the purpose set forth 10 substantially as described.

2. In a design-roller for graining-machines, the combination with two flanged hubs, of wooden sections extending radially from the said hubs, said sections tapering inwardly, 15 an outer covering of sections of design-wood having the grain running in various directions, means to secure said sections to said tapering sections, said tapering sections being mounted in sockets cast or formed upon 20 the hubs of the roller, and a shaft extending through said roller, for the purpose set forth substantially as described.

3. In a design-roller for graining-machines, the combination with two hubs, of wooden 25 sections extending radially from the said hubs, said sections tapering inwardly and having an outer covering of sections of design-wood having the grain running around the roller, said sections being joined in such a 30 manner that there will be no break in transmitting the impression of the grain to the printing-roller, means to secure said sections to said tapering sections, and means to secure said tapering sections to said hubs, for 35 the purpose set forth substantially as described.

4. In a design-roller for graining-machines, the combination with two hubs, of wooden sections extending radially from the said 40 hubs, said sections tapering inwardly and having an outer covering of sections of design-wood having the grain running around the roller, said sections being joined in such a manner that there will be no break in transmitting the impression of the grain to the 45

printing-roller, said tapering sections being mounted in sockets cast or formed on the hubs of the roller, and a shaft extending through said roller, for the purpose set forth substantially as described. 50

5. In a design-roller for graining-machines, the combination with two flanged hubs having a bevel-gear cut upon the outer face of said flanges, of wooden sections extending radially from the said hubs, said sections tapering inwardly and having their outer surface turned true, an outer covering of sections of design-wood having the grain running in various directions, said sections being joined in such a manner that there will be no break in transmitting the impression of the grain to the printing-roller, means to secure said sections to said tapering sections, and means to secure said tapering sections to said hubs, for the purpose set forth substantially as described. 65

6. In a design-roller for graining-machines, the combination with two flanged hubs having a bevel-gear cut upon the outer face of the said flanges, of wooden sections extending radially from the said hubs, said sections tapering inwardly and having their outer surface turned true, said sections being provided with extensions at each end, said extensions extending inwardly and fitting 70 around the said hubs, an outer covering of sections of design-wood having the grain running around the roller, said sections being joined in such a manner that there will be no break in transmitting the impression of the grain to the printing-roller, means to secure said sections to said tapering sections, means to secure said tapering sections to said hubs, and a shaft extending through said roller, for the purpose set forth substantially as described. 75
